(57) **CLAIM**

The ornamental design for a 2U rack-mount chassis front panel, as shown and described.

DESCRIPTION

FIG. 1 is an elevated, perspective view of the 2U rack-mount chassis front panel in accordance with our invention;

FIG. 2 is a front view thereof;

FIG. 3 is a side view thereof;

FIG. 4 is an opposing side view thereof;

FIG. 5 is a top view thereof; and,

FIG. 6 is a bottom view of our invention as shown in FIG. 1.
